United States Patent

Des. 241,749
Patented Oct. 5, 1976

241,749

ELECTRICAL PLUG

Higenia Acosta, 332 E. 14th St.,
New York, N.Y. 10003

Filed Oct. 16, 1975, Ser. No. 623,063

Term of patent 14 years

Int. Cl. D7—04; D13—03

U.S. Cl. D26—1 B

FIG. 1 is an edge elevational view of an electrical plug showing my new design;

FIG. 2 is a view looking from the top of FIG. 1,

FIG. 3 is a view looking from the left side of FIG. 2,

FIG. 4 is a view looking from the right side of FIG. 2.

I claim:

The ornamental design for an electrical plug, as shown.
